UNITED STATES PATENT OFFICE.

WALTER D'A. RYAN AND GEORGE H. STICKNEY, OF LYNN, MASSACHUSETTS, ASSIGNORS TO
GENERAL ELECTRIC COMPANY, A CORPORATION OF NEW YORK.

DESIGN FOR AN ELECTRIC-ARC-LAMP GLOBE.

No. 39,143.

Specification for Design.

Patented Feb. 18, 1908.

Application filed December 9, 1907. Serial No. 405,827. Term of patent 14 years.

To all whom it may concern:

Be it known that we, WALTER D'A. RYAN, a subject of the King of Great Britain, and GEORGE H. STICKNEY, a citizen of the United States, residing at Lynn, county of Essex, State of Massachusetts, have invented a new, original, and ornamental Design for Electric-Arc-Lamp Globes, of which the following is a specification, reference being had to the accompanying drawing, forming part thereof.

The drawing represents an elevation of an arc lamp globe showing our new design.

The globe is constructed in two semispher-

ical parts, the upper part being of metal or other opaque material, while the lower part is of opal glass or other translucent but not transparent glass, through which the lamp structure is visible in shadowy outline.

We claim:

The ornamental design for an electric arc lamp globe, as shown and described.

WALTER D'A. RYAN.
GEORGE H. STICKNEY.
